F. PIATTY

HOROLOGY

Filed Sept. 27, 1924

Inventor

Frank Piatty

534 *William C. Hunter*
Attorney

UNITED STATES PATENT OFFICE.

FRANK PIATTY, OF LEMONT, PENNSYLVANIA.

HOROLOGY.

Application filed September 27, 1924. Serial No. 740,345.

To all whom it may concern:

Be it known that I, FRANK PIATTY, a citizen of the United States of America, residing at Lemont, county of Fayette, State of Pennsylvania, have invented certain new and useful Improvements in Horology; and I do hereby declare that the following is a full, clear, concise, and exact description of the invention, such as will enable others skilled in the art to which it appertains to make and use the same.

This invention relates to improvements in horology, having for an object to provide a water operated clock wherein an indicator is controlled by the discharge of water from the casing for the same to such a nicety as to permit of its accurate indicating of time.

It is likewise an object of the invention to provide a clock of the character mentioned which, by reason of its simplicity of construction, may be advantageously marketed and sold as a novelty, the operation thereof being dependable and accurate due to the elimination of any intricacy of construction or adjustment of the several parts.

Other objects of the invention will be in part obvious, and in part pointed out hereinafter.

In order that the invention and its mode of operation may be readily understood by persons skilled in the art, I have in the accompanying illustrative drawings, and in the detailed following description based thereupon, set out one possible embodiment of the same.

In these drawings:—

Figure 1 is a vertical section through the improved clock having a portion of the lower end of the indicator broken away and shown in section;

Figure 2 is a detail in elevation of the time indicator; and,

Figure 3 is a top plan view of the device.

Having more particular reference to the drawings, in connection with which like characters of reference will designate corresponding parts throughout the several views, the improved device may be stated to comprise a combined supporting base and receptacle 1, herein shown as being circular in its cross sectional shape, said receptacle being water-tight, and having a spout or lip 2 secured to one side of the same, as

shown in the Figure 1, and communicating with an opening 3 in an adjacent portion of the receptacle wall, whereby passage of fluid from the spout into the receptacle, or vice-versa, may be effected, as desired. 60

The upper end of the combined supporting base and receptacle 1 is opened and is adapted to be normally closed by means of a corresponding shaped cover 4 flanged, as indicated at 5, whereby to snugly and frictionally engage adjacent portions of the outer sides of the receptacle walls. 65

Rigidly supported upon the upper side and concentric portion of the cover 4 is a water-tight tube 6, the open lower end thereof being closed by reason of said cover 4, while the upper end thereof is adapted to be normally closed through the medium of a flanged cap 7, shaped in cross section to correspond to the cross sectional shape of said 70 tube 6 and adapted to be snugly engaged over the same as indicated in the Figure 1. This cap 7 is provided with a concentrically arranged squared opening 8, the purpose of which will be presently apparent. 75

A valve controlled discharge spout or spigot 9 is tapped into the lower end of the tube 6 and as will be noted upon reference to the drawings, is adapted to be arranged in vertical alignment with the spout 2; the 80 valve of the spout or spigot being provided with a suitable form of handle 10 whereby to facilitate the desired adjustment of the same.

Passing through the squared opening 8 90 in the cap 7 into the tube 6 is an elongated time indicating bar 11, which as will be noted, is substantially square in cross section, and is snugly received in said opening 8 whereby to prevent material lateral movement of the same with respect to the cap 7 or to the upper portion of the tube 6. Markings 12, indicating the various hours of a day are inscribed upon the various faces of the indicating bar 11 and as will be noted, 95 the spaces between these numerals are divided into sections indicative of portions of an hour. If desired, the spaces between the various hour-indicating numerals 12 may be increased in order that a greater division 100 of the hours may be made than that shown herein. In other words, if desired, the spaces between the hour-indicating numerals 12 may be divided into minutes, or certain groups of minutes other 105 110

than those shown in this particular embodiment, such as conditions or preference may dictate. A float 14 formed of cork or other suitable material, circular in cross section is 5 snugly received within the tube 6 and is secured to the lower and adjacent end of the time indicating bar 11 through the medium of a suitable fastening device 15. In this way, it will be understood that with the 10 placing of liquid 16 in the tube 6, the float 14 will buoyantly support the time indicating bar 11 thereupon.

The modus operandi of the improved clock may be stated to be as follows:

15 The liquid is placed in the tube 6 to a height at which the lowermost numeral 12 upon the time indicating bar 11 will be exposed above the cap 7, the division line at the bottom thereof coinciding with the upper surface of the cap 7 thus indicating, for example, twelve o'clock midday. The handle 10 of the valved spigot 9 is now adjusted to permit the flow of the liquid from the tube 6 into the receptacle 1 by way of 20 the spout 2 and opening 3. The discharge of liquid from the tube 6 is regulated to such a nicety that the float 14 carrying the time indicating bar 11 will descend within the tube 6 in accurate keeping and register 25 with the passing of time. Thus, as the time indicating bar 11 descends in the tube 6, with the continued discharge of liquid therefrom into the receptacle 1, the time of day may be readily ascertained by viewing 30 the uppermost exposed graduation and hour indicating numeral upon the time indicating bar 11. When the liquid 16 has been exhausted from the tube 6, the float 14 will be in its lowermost position within said 35 tube 6 while the upper hour-indicating numeral 12 will be exposed, thus indicating midnight. To repeat the operation, it is only necessary that the closure 4 be removed 40 from the combined supporting base and receptacle 1 whereupon the cap 7 of said tube 6 is removed and the liquid in the receptacle 1 is returned into the tube 6. The receptacle 45 1 is now reengaged by the closure 4 and the spigot 9 is aligned with the spout or lip 2. 50 whereupon adjustment of the valve of said spigot through the medium of its handle 10 is effected to again repeat the discharge of

liquid from the tube 6 at the proper rate to accurately indicate time.

Manifestly, the construction shown is capable of considerable modification, and such modification as is within the scope of my claims, I consider within the spirit of my invention.

I claim:

1. A device of the character described comprising a combined supporting base and receptacle having a spout on one side thereof communicating with the same, a closure snugly engageable over the upper side of said receptacle, a vertically disposed tube rigidly secured to the upper portion of said closure, a float snugly received and slidably within said tube, a time indicating bar carried on the upper side of said float, a closure cap having an opening therein engaged over the upper end of said tube and receiving the time indicating bar through said opening therein, and means for effecting and controlling the discharge of fluid from said tube into the spout of the combined supporting base and receptacle.

2. A device of the character described comprising a combined supporting base and receptacle having a spout communicating with the same, a closure for the open portion of said receptacle snugly engageable over the same, a vertically disposed tube rigidly supported upon the upper and concentric portion of said closure, a float snugly and slidably received within said tube, a time indicating bar, square in cross section, secured at its lower end to said float, the various sides of said bar having hour indicating matter presented thereupon, a closure for the upper end of said tube having an opening therein snugly receiving the adjacent portion of said time indicating bar therethrough whereby to permit of vertical movement of said bar with respect to the tube but to prevent material lateral movement thereof with respect to such tube, and a valved spigot tapped into the lower end of said tube and adapted to vertically align with said spout as and for the purpose set forth.

In witness whereof I have hereunto set my hand.

FRANK PIATTY.
